Des. 188,766
Patented Sept. 6, 1960

188,766

LINK FOR AN ORNAMENTAL CHAIN

Leonard H. Read, 106 Wells Ave., Warwick, R.I.

Filed Apr. 15, 1960, Ser. No. 60,197

Term of patent 14 years

(Cl. D45—4)

F I G. 1

F I G. 2

F I G. 3

F I G. 4

F I G. 5

Fig. 1 is a perspective view of a link for an ornamental chain, showing my new design;

Fig. 2 is a plan view thereof;

Fig. 3 is a side view thereof;

Fig. 4 is an end view thereof; and

Fig. 5 is a sectional view taken on lines 5—5 of Figure 2.

The undisclosed face is substantially the same in appearance as the face shown.

I claim:

The ornamental design for a link for an ornamental chain, substantially as shown and described.
